US00D844561S

(12) **United States Design Patent** (10) **Patent No.:** **US D844,561 S**
(45) **Date of Patent:** **** Apr. 2, 2019**

(54) **SWITCHING POWER SUPPLY**

(71) Applicant: **Guangzhou Yihua Electronic Equipment Co., Ltd.**, Guangzhou, Guangdong (CN)

(72) Inventor: **Mingkang Gou**, Guangdong (CN)

(73) Assignee: **GUANGZHOU YIHUA ELECTRONIC EQUIPMENT CO., LTD.**, Guangzhou, Guangdong (CN)

(**) Term: **15 Years**

(21) Appl. No.: **29/606,251**

(22) Filed: **Jun. 2, 2017**

(30) **Foreign Application Priority Data**

Dec. 8, 2016 (EM) 003507268-0012

(51) LOC (11) Cl. **13-02**

(57) **CLAIM**

The ornamental design for a switching power supply, as shown and described.

DESCRIPTION

FIG. 1 is a perspective view of the switching power supply showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures depict portions of the article which form no part of the claimed design.
